Primary Examiner — Jack Reickel*Assistant Examiner* — Michael A Kervin(74) *Attorney, Agent, or Firm* — Jose Cherson Weissbrot(57) **CLAIM**

The ornamental design for a shower curtain rod, as shown and described.

DESCRIPTION

FIG. 1 is a perspective view of a shower curtain rod showing my new design;
FIG. 2 is another perspective view thereof;
FIG. 3 is a front elevational view thereof, the rear elevational view being a mirror image of FIG. 3;
FIG. 4 is a left elevational view thereof, the right side view being a mirror image of FIG. 4;
FIG. 5 is a top side view thereof, the bottom plan view is identical;
FIG. 6 is a partial enlarged view of FIG. 1; and,
FIG. 7 is a perspective view of the shower curtain rod in an extended state.
The broken lines in the figures are for the purposes of illustrating portions of the shower curtain rod, which form no part of the claimed design.
